UNITED STATES PATENT OFFICE.

JOHN H. STAYTON BONNER AND MARTIN TOWNSEND CHAMBERLIN, OF WICHITA FALLS, TEXAS.

PUMP.

Application filed April 3, 1925. Serial No. 20,475.

To all whom it may concern:

Be it known that we, JOHN H. STAYTON BONNER and MARTIN TOWNSEND CHAMBERLIN, citizens of the United States, residing 5 at Wichita Falls, in the county of Wichita, State of Texas, have invented certain new and useful Improvements in Pumps, of which the following is a specification.

This invention relates in general to pumps, especially designed for use with oil wells and aims to provide a pump of this character of such construction as to provide a thoroughly effective sand trap, a gas anchor, and a means for preventing a vacuum sometimes set up in the well from interfering with the operation of the pump, whereby to prolong the life of the pump and render it more efficient in operation, and less expensive to maintain. 10 A further object is the provision of a pump having these advantages and capacities and which is of simple and durable construction, reliable in operation, and easy and comparatively inexpensive to manufacture and maintain. 20

Other objects and advantages reside in certain novel features of the construction, arrangement and combination of parts which will be hereinafter more fully described and particularly pointed out in the appended claims, reference being had to the accompanying drawings, forming a part of this specification, and in which,—

Figure 1 is a view in elevation showing 35 one embodiment of the invention.

Figure 2 is an enlarged fragmentary view in diagrammatic vertical section of the pump shown in Figure 1, and

Figure 3 is a view in transverse section on 40 the line 3—3 of Figure 2.

Referring to the drawings the numeral 1 designates the tubing which constitutes the flow line and on which the pump embodying the present invention is suspended. Of course the sucker rods operate through the flow line 1 in the usual manner. A working barrel 2 is carried by the lower end of the flow line 1 and at the lower end of the working barrel a standing valve 3 is provided. It is to be understood that the usual plunger (not shown) operates in the working barrel and is actuated by the sucker rods.

The present invention proposes the provision of a casing, designated generally at

4, made up of sections 5, 6, 7, 8 and 9 suitably connected. The sections 5, 6, 8 and 9 are cylindrical and are tubular but the section 7 while cylindrical is not tubular although formed with a number of openings 60 as will be hereinafter more fully described. The section 7 provides a partition which divides the casing into an upper inlet chamber 10 and a lower chamber 11 which constitutes a sand trap. As shown in the 65 drawings, the upper section 5 of the casing is reduced, as at 5^a, so as to snugly fit around the tubing 1. A set screw 12 is employed for securing the casing 4 to the tubing 1. The arrangement is such that the tubing 1 70 and the working barrel 2 carried thereby are eccentric with respect to the casing 4. The section 5 of the casing 4 is formed with a plurality of inlet openings 13, which may or may not be screened, so as to permit the 75 oil or other fluid to pass into the chamber 10. The section 9 of the casing 4 has its lower end closed by a plug or head 14, so that the chamber 11 is closed except for its communication with the chamber 10 which 80 is had through openings 15 provided in the section 7.

A number of tubes 16 are fitted and held in openings 17 provided thereby in the section 7, the lower ends of the tubes 16 being 85 in open communication with the chamber 11 and the upper ends of the tubes 16 being closed, as at 18, and being located in the chamber 10. The interior of the tubes 16 communicates directly with the chamber 11 90 but communicates with the chamber 10 only through the chamber 11. Stand pipes 19, which are smaller than the tubes 16 extend up into the tubes to a point adjacent to but spaced from their upper closed ends 18. 95 The lower ends of the stand pipes are connected by elbows 20 to a cylinder 21, the lower end of which is closed, as at 22, and the upper end of which is received and secured in an opening 23 provided in the 100 section 7. Just above the upper end of the cylinder 21 the valve seat 3^a for the standing valve is provided and as shown in the drawings this valve seat 3^a may be a part of the section 7. The lower end of the 105 working barrel 2 terminates above the valve seat 3^a and the working barrel and cylinder are in alignment.

With a pump of this character the fluid passes through the openings 13 into the 110

chamber 10 and from the chamber 10 down through the openings 15 into the chamber 11. This downward coursing of the fluid tends to precipitate sand or dirt to the bottom of the chamber 11, especially as the fluid after passing downwardly into the chamber 11 must change its course and move up through the tube 16. After travelling to points adjacent the tops of the tubes 16 the fluid again reverses its direction of flow and moves down through the stand pipes 19 and elbows 20 and into the cylinder 21. Again the downward course flow of the fluid tends to precipitate sand, dirt, or the like, in the cylinder 21, especially as the fluid after entering the cylinder 21 while flowing downwardly must reverse its direction of flow and pass upwardly through the standing valve 3 into the working barrel 2. The arrangement shown not only has the effective action just described to trap the sand, but the standing valve being isolated from the well by the double column of fluid, and subjected to the weight of said column of fluid, will not become stuck by virtue of the vacuum in the well. Moreover, the arrangement provides a gas anchor so that in the one device there is the combined action of a sand trap, gas anchor, and a means for preventing the vacuum from interfering with the operation of the pump.

We claim:

1. In an oil well pump having a working barrel provided with a standing valve, a casing enclosing the working barrel, said casing having a section dividing the casing into an upper inlet chamber and a lower sand trap chamber, a tube mounted on the section and communicating at its lower end with the sand trap chamber, the upper end of the tube being closed, a stand pipe extending up into the tube and communicating with the upper part of the tube at its upper end, and a cylinder connected to the working barrel and communicating with the lower end of the stand pipe at its lower end.
2. In an oil well pump having a working barrel provided with a standing valve, a casing eccentrically disposed of and secured to the working barrel so as to enclose the same, said casing having a section pro-

viding an upper inlet chamber and a lower sand trap chamber, a plurality of tubes carried by said section, said tubes having their upper ends closed and located in the inlet chamber and their lower ends open and communicating with the sand trap chamber, said section having openings affording communication between the inlet chamber and the sand trap chamber, a plurality of stand pipes extending up into the tubes and having their upper ends communicating with the upper portions of the tubes, and a cylinder carried by the section and connected with the lower ends of the stand pipes, the upper ends of the cylinder communicating with the working barrel and the lower end of the cylinder being closed.

3. In an oil well pump including tubing, a working barrel carried by the tubing and a standing valve associated with the working barrel, a casing enclosing the working barrel and eccentrically disposed thereof, the upper end of the casing snugly fitting around the tubing, the lower end of the casing being closed, means for securing the upper end of the casing to the tubing, said casing having a section defining an upper inlet chamber and a lower sand trap chamber, the casing having openings adjacent its upper end and leading into the inlet chamber, the said section having an opening receiving the lower end of the working barrel, a plurality of vertical tubes having their upper ends closed and having their lower ends open, said section having openings receiving the lower ends of the tubes, the tubes communicating with the sand trap chamber, said section having openings affording communication between the inlet chamber and the sand trap chamber, a plurality of stand pipes extending up into the tubes, the upper ends of the stand pipes being open, a cylinder carried by the section and communicating with the working barrel, said cylinder being connected with the lower ends of the stand pipes, said cylinder having its upper end in communication with the working barrel and having its lower end closed.

JOHN H. STAYTON BONNER.
MARTIN TOWNSEND CHAMBERLIN.
